UNITED STATES PATENT OFFICE

2,194,899

APPARATUS FOR PRODUCING LIGHT OF VARIABLE COLOR EFFECTS

Johan Alfred Hansson, Trelleborg, Sweden

Application April 10, 1939, Serial No. 267,150
In Sweden April 26, 1938

8 Claims. (Cl. 240—10.1)

The present invention refers to apparatus for producing light of variable color effects, of the type which are provided with a light source and a substantially cylindrical light screen which is 5 rotatably mounted around said light source and the peripheral surface of which is composed of a plurality of preferably differently colored bands or strips, said screen being rotatable under the action of an ascending air current which is 10 produced by the light source.

The principal object of the invention is to provide an apparatus of this type which is capable of producing color effects in the form of a train of alternating colors similar to a flash 15 light or imitating flames of fire.

Another object of the invention is to provide an apparatus of the type referred to which, when placed in an open fireplace or hearth and concealed for example by logs of wood, will give 20 the impression of a burning fire with ascending flames and smoke.

A further object of the invention is to provide an apparatus which may be mounted within a transparent or translucent light globe and used 25 as an advertising or display apparatus in shop-windows and the like.

The invention will be more fully described in a preferred form with reference to the accompanying drawing, in which:

30 Fig. 1 shows a side view of the apparatus according to the invention, part of the outer light screen of the apparatus being broken away to expose the parts behind it;

Fig. 2 is a transverse section on the line II—II in Fig. 1;

35 Fig. 3 is a transverse section on the line III—III in Fig. 1; and

Fig. 4 shows a plan view of the upper part of the apparatus.

40 Referring to the drawing, 1 designates an electric incandescent lamp which is vertically supported by a base 2. The lamp 1 is provided on its upper part with an elastic clamp or holder 3 which embraces the lamp bulb and carries an upwardly projecting pointed needle 4. Upon 45 this needle rests a cap 5 forming a bearing which is secured to a screen 6 surrounding the incandescent lamp and comprising a cylindrical portion composed of a plurality of differently colored, for example alternately yellow and red, 50 transparent or translucent bands or strips 7 and intermediate clear spaces 8, see Fig. 2. The colored strips extend parallel to each other and to the axis of the screen cylinder. At the top the screen 6 is terminated by propeller blades like-

wise of two different colors which are carried by a spider and the radial edges of which overlap each other.

The colored screen 6 is surrounded by an outer stationary screen 10 mounted on the base 2 and having a cylindrical peripheral surface which is slit in such a manner that it comprises a plurality of slots 11 extending in the longitudinal direction of the peripheral surface and impervious bands or strips 12 which are disposed in 10 an oblique position as is shown in Fig. 2 of the drawing. The strips 12 are substantially plane throughout their length. The screen 10 is terminated at its top by a fine-meshed net 15 which is fastened into a ring 13 and protected by guard 15 wires 14. The strips 12 have smooth inside surfaces which serve as a reflector and black-lacquered outer surfaces.

The apparatus is primarily intended to be placed in open fireplaces, hearths or the like, 20 logs of wood or the like being piled around the apparatus. When the light source within the apparatus is switched on to emit light, the air current produced around the light source due to the heat therefrom causes the propeller blades 25 to rotate the inner colored screen 6. The light from the light source coming out through each slot 11 has first alternately passed colored strips 7 and spaces 8 of the screen 6, so that said light is in the form of flashes of alternating colors, 30 i. e., white and colored light, and causes the illusion of ascending flames of fire in a very natural manner. The light reflected upwardly through the propeller blades and the net causes the illusion of ascending smoke through the 35 provision of said net. The total effect of the apparatus is thereby such as to cause an impression of a burning fire in the open fireplace or the like provided with the apparatus.

The apparatus may also be disposed within a 40 transparent or translucent lamp globe to produce a flickering light of alternating colors upon the wall of said globe. The entire unit may be placed for example in a show-window or the like and used as an advertisement apparatus. 45

The invention must not be considered limited to the form thereof here described and shown in the drawing, as it may be varied in several ways without exceeding the general scope of the same. The oblique position of the strips 12 50 shown in Fig. 2 has proved advantageous, where the colored screen 6 rotates in the direction indicated by the arrow in said figure, since there by the air flowing in through the outer screen obtains the same direction of movement as the 55

colored strips 7 of the inner screen, but it is also practicable to use an otherwise oblique position of said strips 12. Although the colored strips have been shown extending vertically and parallel to the axis of the cylindrical screen 6, they may also be placed in an inclined position in relation to said axis. Further, the edges of the colored strips need not be straight but may also for example be corrugated in a plane at right angles to the plane of the strip. The slots 11 may be wider than shown in the radial direction. An arbitrary number of different colors may be used for the strips of the inner screen, as desired for various purposes.

15. What I claim and desire to secure by Letters Patent is:

1. An apparatus for producing light of variable color effects, comprising a base, a light source, a substantially cylindrical inner screen rotatably mounted around said light source, the peripheral surface of said inner screen being composed of a plurality of colored, light transmitting strips, means for rotating said inner screen under the action of an ascending air current produced by said light source, a stationary, substantially cylindrical outer screen mounted on said base round the outside of the inner screen and composed of a plurality of alternately impervious and transmitting strips extending substantially in the axial direction of said outer screen, said impervious strips being disposed in an oblique position in relation to the peripheral surface of said outer screen.

2. An apparatus for producing light of variable color effects, comprising a base, a light source supported by said base, a substantially cylindrical inner screen rotatably mounted around said light source, the peripheral surface of said inner screen being composed of a plurality of colored, light transmitting strips, means for rotating said inner screen under the action of an ascending air current produced by said light source, a stationary, substantially cylindrical outer screen mounted on said base round the outside of the inner screen and composed of a plurality of alternately impervious and transmitting strips extending substantially in the axial direction of said outer screen, said impervious strips being disposed in an oblique position in relation to the peripheral surface of said outer screen.

3. An apparatus for producing light of variable color effects, comprising a base, a light source, a substantially cylindrical inner screen rotatably mounted around said light source, the peripheral surface of said inner screen being composed of a plurality of colored, light transmitting strips separated by intermediate clear spaces, means for rotating said inner screen under the action of an ascending air current produced by said light source, a stationary, substantially cylindrical outer screen mounted on said base round the outside of the inner screen and composed of a plurality of alternately impervious and transmitting strips extending substantially in the axial direction of said outer screen, said impervious strips being disposed in an oblique position in relation to the peripheral surface of said outer screen.

70. 4. An apparatus for producing light of variable color effects, comprising a base, a light source, a substantially cylindrical inner screen rotatably mounted around said light source, the peripheral surface of said inner screen being composed of a plurality of colored, light trans-

mitting strips, propeller means at the top of the inner screen for rotating said inner screen under the action of an ascending air current produced by said light source, a stationary, substantially cylindrical outer screen mounted on said base round the outside of the inner screen and composed of a plurality of alternately impervious and transmitting strips extending substantially in the axial direction of said outer screen, said impervious strips being disposed in an oblique position in relation to the peripheral surface of said outer screen.

5. An apparatus for producing light of variable color effects, comprising a base, a light source, a substantially cylindrical inner screen rotatably mounted around said light source, the peripheral surface of said inner screen being composed of a plurality of colored, light transmitting strips, means for rotating said inner screen under the action of an ascending air current produced by said light source, a stationary, substantially cylindrical outer screen mounted on said base round the outside of the inner screen and composed of a plurality of impervious strips separated by slots, said impervious strips extending substantially in the axial direction of said outer screen and being disposed in an oblique position in relation to the peripheral surface of said outer screen.

6. An apparatus for producing light of variable color effects, comprising a base, a light source supported by said base, a substantially cylindrical inner screen rotatably mounted around said light source, the peripheral surface of said inner screen being composed of a plurality of colored, light transmitting strips, means for rotating said inner screen under the action of an ascending air current produced by said light source, a stationary, substantially cylindrical outer screen mounted on said base round the outside of the inner screen and composed of a plurality of alternately impervious and transmitting strips extending substantially in the axial direction of said outer screen, said impervious strips being disposed in an oblique position in relation to the peripheral surface of said outer screen, a lid closing the outer stationary screen at the top thereof and comprising impervious and transmitting portions.

7. In an apparatus as claimed in claim 6 the additional feature that said lid closing the outer stationary screen at the top thereof consists of a fine-meshed net.

8. An apparatus for producing light of variable color effects, comprising a base, a light source, a substantially cylindrical inner screen rotatably mounted around said light source, the peripheral surface of said inner screen being composed of a plurality of colored, light transmitting strips, means for rotating said inner screen under the action of an ascending air current produced by said light source, a stationary, substantially cylindrical outer screen mounted on said base round the outside of the inner screen and composed of a plurality of impervious strips separated by slots, said impervious strips extending substantially in the axial direction of said outer screen and being disposed in an oblique position with their leading longitudinal edges, as seen in the direction of movement of the inner screen, situated radially within the trailing longitudinal edges of said impervious strips.
